PROTECTOR BOOT FOR THE ENDS OF
ROLLS OF PAPER AND THE LIKE

Virgil E. Scott, Portland, Oreg.

Application March 16, 1932, Serial No. 599,192

4 Claims. (Cl. 206—59)

Rolls of paper, which are heavy, for example the rolls of printing paper supplied to newspapers, when handled in loading, unloading or storing, are, because of their weight, trundled or rolled over the ground on an end. Such trundling places a great strain on the trundling edge of the roll, and more or less crushes and tears away the outer windings of the sheet composing the roll, and so causes a waste and loss which frequently is considerable.

To protect the roll ends against such damage and waste, the ends are wrapped with a band of strong paper, but this protector-wrapping is insufficient to prevent said damage, because the heavy weight imposed on the trundled roll end tends to strip off the protective covering band, or mash the edge of the roll; and frequently does both.

I have discovered that an efficient and convenient way of protecting the edge of the roll end is to place over it a protector boot. This boot must be adapted to be readily secured on the roll end, and besides, must be adapted to provide an exterior buffer-protrusion; and preferably should provide an interior annular space about the edge of the inclosed roll end, so as to prevent the transmission of any stresses from the sole or leg of the boot to the edges of the sheets composing the roll, while the roll is being trundled on its end.

Where the boot is made of a substantially rigid material, paper, for example, the providing of the said exterior buffer protrusion will give sufficient protection without said interior space. But if no interior space is provided about the edge, and the boot leg is made of material more or less yielding, in consequence the sole of the boot will bear firmly on the edge of the roll, then any stress imposed on the sole of the boot, in the trundling of the roll on end, would most likely be transmitted to the edges of the outer windings of the sheet composing the roll, and cause them to be more or less mashed, and require these outer windings to be stripped off and wasted.

Furthermore, the sole of the boot should be provided with a heel so arranged that the trundling of the roll on an end as mentioned will not transmit any strain to the edge of the roll end. Preferably this heel should be located inward from the circumference of the roll end, so that no stress will be imposed on the edge of the roll end, in tilting and trundling the roll on end. When the heel is arranged as mentioned, then the stresses transmitted to the roll end would be located a substantial distance inward of the circumference of the roll end, thus at a point where

the solidity of the winding of the sheet making up the roll is well able to stand such stresses without injury to the edges of the outer sheets composing the roll end.

My protector boot further serves as a protective buffer for the roll ends. In the placing of a roll close to another roll it frequently happens that the roll being moved into place strikes against another roll with such force as to damage the latter. By my protective boot such damage is avoided, by the resilient buffer protrusion provided about the inclosed edge of the roll.

My protective boot is preferably made of elastic material, specifically rubber, and in that way it is adapted to be placed on rolls of varying diameters. In other words, the leg of the boot is adapted to fit snugly over the roll of a given minimum diameter, but may be stretched over rolls of much greater diameter; in either case, the elasticity of the material secures the upper part of the boot leg firmly in place on the roll end.

By placing my protective boot on both ends of rolls of paper, chafing and resulting injury and damage frequently incurred in the transportation of rolls is prevented.

Furthermore, by making my protective boot with a sole that extends all the way across the bottom of the boot; the roll end on which my protective boot is affixed is effectively protected against moisture on the ground on which the roll is stood.

Where the sole of the boot extends all the way across it may be provided with a knob-like protrusion at the center on which the roll, when stood on end, may be tilted sufficiently to facilitate the picking up of the roll by a hand-truck.

Furthermore, when using my protector boot, only a very light paper wrapping or covering of the roll ends is required, in that way saving both in time and material over the present heavy wrapping of the roll ends.

My invention is susceptible to modifications in details of construction and the arrangement of its elements.

I attain the foregoing objects and incidental features in the protector-boot hereinafter described, reference being had to the accompanying drawings.

In the drawings:

Fig. 1 shows, partly in section and partly in elevation, the lower end of a roll of paper on which my protector-boot is placed. This figure further shows a knob inserted in the end of the hollow core of the roll, to tilt the roll slightly, and thus

facilitate the picking up and moving of the roll by a hand truck;

Fig. 2 shows a view similar to Fig. 1, but illustrates a modification in the arrangement of the heel of the boot. This figure further shows a wire band imbedded in the sole to prevent stretching of the latter cross-wise;

Fig. 3 shows a fragmentary top view of the type of protector-boot shown by Fig. 2;

10 Fig. 4 shows a view like Fig. 1, but illustrates a further modification of the sole of the boot; also shows how the latter may be made to include a central knob-like protrusion to tilt the roll slightly on its end, as mentioned;

15 Fig. 5 shows, by a view similar to Fig. 1, a still further modification which may be made in the arrangement of the elements of my invention, and illustrates the inclusion in the sole of a fabric ring to prevent stretching of the sole cross-wise;

Fig. 6 shows a fragmentary bottom view of my protector boot as constructed in Fig. 4; and

20 Fig. 7 shows a more simple mode of constructing my boot; as here shown the interior annular space offset from the edge of the roll on which the boot is placed, is omitted.

Referring first to Fig. 1: *a* represents a roll of paper wound on a hollow core *b*. The lower end of the roll *a* is inclosed by my protector-boot *c*,

30 which, for convenience, is shaped to represent a segment of a sphere. The protector boot includes a leg *c'* and sole *d* provided with a heel *e*. The latter is of annular construction, and preferably the outer, circumferential face of the heel

35 *e* should be set slightly inward of the circle represented by the circumference of the roll. In that way, any stress imposed on the heel while the roll is trundled on end, will not be transmitted to the outer edge of the circumference of

40 the roll, where the windings of the sheet are easily displaced and damaged, but instead such stresses are applied a substantial distance inward of the circumference of the roll, and thus to the more solidly wound portion of the roll.

45 which is able to sustain such stresses without injury to the outer windings of the sheet composing the roll.

The protector-boot is preferably made of an elastic material, specifically rubber, and the top

50 of the boot-leg *c'* must be adapted to affix itself to the circumference of the roll by normal contraction of the circle described by the top of the boot. In order to obtain such effect and provide for the use of my protector-boot on rolls of varying diameters, the leg of the boot should be adapted to be affixed as mentioned to a roll of given minimum diameter, while the elasticity

55 of the leg *c'* should be adapted to permit the placing of the protector-boot on roll-ends of

60 much greater diameter.

The boot-leg *c'* is preferably reenforced at the

top with a bead *f*, as shown in Fig. 1.

In the center of the roll there is preferably inserted in the hollow core *b*, a knob-like protrusion *g* of semi-spherical contour, the base of which projects beyond the plane touched by the bottom of the heel *e*; this facilitates the tilting of the roll, when stood on end, to such extent as to conveniently use a hand truck for picking up and moving the roll.

Referring next to Fig. 2: The construction here shown of my protector-boot, as will be noted, is very similar to that illustrated by Fig. 1, except that the heel *h* is made with exterior and interior peripheral faces *i*, *i'* which converge downward

ly. Thus, the bearing point *j* in this type of heel is located inward of the circle described by the circumference of the roll substantially in the same way as the exterior periphery of the heel *c'* is located by the construction shown in Fig. 1.

The heel *h* of the boot may be provided with a wire ring *h'* embedded in the heel, to prevent the sole *d* of the boot from being stretched cross-wise. The stretching of the sole of the boot cross-wise might pull it off the roll end.

80 In Fig. 4 the construction of my protector-boot is shown as substantially similar to that shown in Fig. 1, except that in this instance the sole *d* is adapted to be spaced from the edge of the roll so as not to transmit thereto any stresses from the heel, and further, the sole is provided with an integral web *k*, the central portion of which is formed with a knob-like protrusion *l*, which functions to tilt the roll slightly when stood on end, so as to facilitate the picking up and moving of

85 the roll, in similar manner as such result is attained by the knob-like device *g* inserted in the hollow core *b*, shown in Fig. 1.

90 The further advantage of the construction shown in Fig. 3, namely, making the bottom of the sole extend entirely across the shoe is, should the roll be stood on damp or moist ground its end is effectively protected against being damaged by the moisture.

95 In Fig. 5 I illustrate a still further modification of my protector-boot. In this case the sole *m* at the periphery of the boot flares outward and downward, and the leg *n* of the boot flares in a similar manner, and joins with the sole to pro-

100 vide an interior space *o*, so arranged that neither the sole of the boot, nor the leg of the boot can touch the circumferential edge *p* of the roll, thus protecting the outer windings of the sheet against any stresses being transmitted by the rim of the

105 sole of the protector-boot to the edge of the roll. The sole *m* of the protector-boot has embedded in it a canvas ring *q*, also serving to prevent the stretching of the sole cross-wise.

110 The primary purpose of my protector-boot is, as above mentioned, to prevent the transmission of stresses from the sole or the leg of the boot at the sole to the edges of the sheet composing the

115 sheet roll because of such damage.

120 In short, the exterior of my protector-boot is adapted to provide a buffer protection, and the interior of the boot to provide an annular space about the edge of the roll and inclosed, thus effectively protecting the edge from all injury.

125 Referring to Fig. 7; this shows my protector boot as made of a more or less stiff, practically unyielding material, for example a form made of paper. The boot *s* has only the exterior buffer protrusion *t*; the interior annular offset space described of the other types being omitted.

130 This type of protector boot should be made in two parts, so that it can be applied readily and the parts secured in place by having a band wound around them.

135 This type of my protector boot may be preferred where paper mills deem it more economical to make the protector boots in the mill; the boot to serve only during the shipment, and to be thrown away on the roll arriving at its destination.

140 I claim:

1. A cylindrical protector boot for an end of a roll of material comprising a leg portion terminating in a sole of greater diameter than the roll,
